UNITED STATES PATENT OFFICE.

AMOS E. SHROCK AND JOSEPH LEHMAN, OF GOSHEN, INDIANA.

HAND BROADCAST-SEEDER.

SPECIFICATION forming part of Letters Patent No. 315,562, dated April 14, 1885.

Application filed September 30, 1884. (No model.)

To all whom it may concern:

Be it known that we, AMOS E. SHROCK and JOSEPH LEHMAN, citizens of the United States, residing at Goshen, in the county of Elkhart and State of Indiana, have invented certain new and useful Improvements in Hand Broadcast-Seeders; and we do hereby declare that the following is a full, clear, and exact description of the same, reference being had to the annexed drawings, making a part of this specification, and to the letters and figures of reference marked thereon.

Figure 1 of the drawings is a perspective view of our improved broadcast-seeder; Fig. 2, an under side plan view with the seed-distributer wheel and means for operating it removed; Fig. 3, a longitudinal section of the seeder, and Fig. 4 a detail perspective view of the feeding-plate.

The present invention has relation to certain new and useful improvements in hand broadcast-seeders; and it consists in the details of construction, substantially as shown in the drawings, and hereinafter described and claimed.

In the accompanying drawings, A represents the usual flexible grain-holder, which may be provided with means for suspending it from the operator, said flexible holder being connected to the hopper B, through which the grain is discharged. This chute or hopper B is connected to the upper side of a rectangular base, C, having at its forward end a transverse opening, a, for the discharge of the seed onto the usual distributer-wheel, D, secured to the vertical drum b. The drum b is rigidly connected to a spindle, c, having its bearings in the base C and the longitudinal brace E. The distributing-wheel is caused to revolve by means of the cord d, which is wound around the drum b and its ends or extremities fastened to the ends of a reciprocating rod, F, provided with coiled springs e, one upon each end of the rod, to form buffers when coming against the ends of the transverse bracket G. The upper end of the spindle c is provided with an eccentric, f, which works in a yoke, g, cast on the forward end of a feed-plate, H, by which means the feed-plate is given a lateral reciprocating motion as the wheel is revolved. This wheel D consists of a concave

bottom, h, with radial arms i and separating wings k, as shown more clearly in Fig. 1. The feeding-plate H is cast or otherwise provided with a bar, l, which extends back from the rear of the plate, and is pivoted at its extremity to a lever, I. One end of the lever I is pivoted to the base C, and its opposite or free end passes through a guide and stop, m, which limits the movement of the lever. By moving back the lever the feeding-plate will also be carried back from under the opening h in the hopper, thus allowing the free discharge of the seed when the machine is in operation, a suitable spring, n, forcing the lever back to its normal position when released by the operator.

In order to limit the extent to which the feeding-plate H is to be drawn back in controlling the discharge of the seed through the opening a, a gage-rod, J, is provided, against which strikes the lever I, thus limiting the stroke or backward throw of the lever I, and the feeding-plate correspondingly, which regulates the opening in the hopper. A curved guard, K, extends transversely under the base C in the rear of the distributing-wheel D, the ends projecting some distance beyond the sides of the base, which prevents the seed from being thrown to the rear of the machine.

The metal bracket G, which forms a bearing for the reciprocating rod F, consists of a rectangular plate or bar having its ends turned up, with holes through which passes the rod. The advantages of this bracket are that it prevents all wear and tear on the wooden portion of the machine and confines all such wear and tear to the upwardly-bent ends of the bracket, the ends of the spiral springs on the rods striking against them, and not against any other part of the machine. The drum b, being directly under the distributing-wheel D, gives the seed a chance of being distributed freely and not coming in contact with any obstacle, such as the cord of the rod. The seed as it is distributed from the wheel D strikes against the curved guard K, which is made very wide. All the seed is freely scattered and distributed, and none drops down by the operator. By the employment of the spring n the front edge of the feeding-plate H is kept pressed tightly against a transverse flange, p, which effectually

prevents the escape of seed when the machine is not in operation, forming a tight joint between the two.

The feeding-plate H differs from others heretofore in use, in that it has a flanged rim, r, projecting upward and extending along the rear and right and left sides of the plate. This flanged rim is cast with the plate, and the advantages of such construction are that it effectually closes the discharge-opening in the hopper and prevents the seed from working out at the sides and rear of the plate, while the strip or flange in front of the opening prevents the seed from escaping at that point.

15 The raised edges or flanged rim of the feeding-plate is held against the under side of the base C by means of a transverse rod, L, removably connected to said base. The rod L, which I shall term a "clamping-rod," may be held against the feeding-plate with any degree of tightness by set-screws s, which also removably secure the rod to the base C.

In order to strengthen the point of connection between the plate H and arm l, that part 25 of the arm where it meets the plate is cast with a bifurcation, as shown at t, and the front of said plate is cast with a frame, M, terminating at its forward end in a yoke, g, hereinbefore described. The plate H is formed at 30 its front edge with the usual feed-distributing recesses, u. The outer or under side of the feeding-plate H is cast with bearing-ribs v at its sides, against which the transverse clamping-rod comes in contact, so as to prevent the 35 surface of the plate coming in contact with the rod throughout its entire length, thereby decreasing the frictional surface between the rod and plate when the latter has imparted to it a lateral reciprocating motion and a longitudinal motion by means of the lever.

The peculiar construction of the plate for

feeding the seed to the wheel is considered important and essential in rendering it successful in its operation, and the adjustable and detachable clamping-rod serves most effectually 45 to steady and guide the feeding-plate in its movement, as well as to keep the flanged rim upon the inner or upper side thereof snugly against the under surface of the base C.

Having now fully described our invention, 50 what we claim as new, and desire to secure by Letters Patent, is—

1. In a hand broadcast-seeder, a laterally reciprocating or vibratory feeding-plate, cast at its front or outer edge with a frame and 55 yoke and having an upwardly-projecting flanged rim extending along the rear and right and left sides, in combination with a suitable lever and gage-rod for operating the plate, and a clamping-rod extending across the plate upon 60 the under side thereof, substantially as and for the purpose set forth.

2. In a hand broadcast-seeder, a suitable grain holder and hopper, a distributing-wheel, and means for operating it, and a transverse flange 65 or strip secured to the under side of the base of the hopper in front of the discharge-opening, in combination with a feed-plate provided with a pivoted hand-lever and gage, said plate having an upwardly-projecting flanged rim 70 along the rear and sides, and bearing-ribs upon the outer or under side of the plate, and a clamping-rod for holding the same in position, substantially as and for the purpose specified.

In testimony that we claim the above we 75 have hereunto subscribed our names in the presence of two witnesses.

AMOS E. SHROCK.
JOSEPH LEHMAN.
